CLAIM

The ornamental design for exercising apparatus for foot, as shown and described.

DESCRIPTION

1. Exercising apparatus for foot

1.1 : Perspective

1.2 : Front

1.3 : Back

1.4 : Top

1.5 : Bottom

1.6 : Right

1.7 : Reference view of state in use

1.8 : Reference view of state in use

The left side view is omitted because it is a mirror image of the right side view.

The broken line showing of a foot is included for the purpose of illustrating portions of the "article" and forms no part of the claimed design.
